UNITED STATES PATENT OFFICE.

CLINTON E. WOODS, OF WATERBURY, CONNECTICUT, ASSIGNOR TO SCOVILL MANUFACTURING COMPANY, OF WATERBURY, CONNECTICUT, A CORPORATION OF CONNECTICUT.

MOUNTING FOR PHONOGRAPH MOTORS.

Application filed May 1, 1920. Serial No. 378,033.

To all whom it may concern:

Be it known that I, CLINTON E. Woods, a citizen of the United States, residing at Waterbury, county of New Haven, and 5 State of Connecticut, have invented certain new and useful Improvements in Mountings for Phonograph Motors, fully described and represented in the following specification and the accompanying drawings, forming a 10 part of the same.

This invention relates to phonographs and particularly to the mounting for the motor mechanism.

In the usual phonograph construction, the 15 turntable is mounted on a motor driven spindle to rotate above a cabinet shelf, on which is mounted the stopping brake and other parts. In order that the brake member may properly align with the edge of the 20 turntable, the latter should have a given elevation above the cabinet shelf. With heretofore known methods of mounting the motor in the cabinet, the given elevation of the turntable was not always maintained, 25 as the cabinet shelves vary in thickness, by warping and the like.

It is the principal object of the present invention to provide a phonograph construction such that the turntable may always have a given elevation above the cabinet shelf.

It is a further object of the invention to provide a compact, conveniently assembled motor unit that may readily be mounted in 35 ready made cabinets to fulfill the conditions above mentioned, without the necessity of carefully positioning and adjusting the parts of each machine.

With these general objects in view, the 40 invention consists in the combinations, details of construction and arrangements of parts which will first be described in connection with the accompanying drawing and then more particularly pointed out.

45 In the drawing,

Figure 1 is a view, partly in vertical section, and partly in elevation, of a portion of a phonograph constructed in accordance with the invention.

50 Figure 2 is a similar view taken on a section at right angles to that of Fig. 1; and

Fig. 3 is a similar view, with parts removed, taken on a different section.

55 Referring to the drawing there is provided a cabinet shelf, exemplified at 11, hav-

ing a circular opening 12 formed therein. The invention includes a motor mechanism including a turntable spindle, and means for so supporting the motor mechanism from the cabinet shelf that the spindle will have 60 a given projection above the shelf regardless of the thickness of the latter. This may be accomplished, for example, by suspending a base plate from the top of the cabinet shelf and supporting the motor mechanism 65 entirely by bearings carried by the base plate.

Although capable of various constructions, in that shown, there is provided a base plate 13 having a bottom rib 14 to 70 which is attached a housing 15. Carried by the base plate are bearings for the motor parts and in structures embodying the invention to the best advantage, two bearings are provided, one being cast integral with 75 the base plate, the other being separate. As here illustrated, secured to the base plate, by screws 16, is a separate bearing bracket 17, which supports a stud 18.

Mounted on the latter is a winding gear 19 80 for the usual motor spring represented conventionally by the spring housing 20. The winding gear 19 meshes with a pinion 21 on a winding shaft 22, journaled in part of the bearing 17. On the opposite side of the 85 spring housing is a driving gear 23 rotated by the spring in the well known manner.

Depending from the base plate and cast integral therewith is a second bearing bracket 24. Journaled in this bearing and 90 in a boss 25 in the base plate through which it extends, is the turntable spindle 26. For part of its length the spindle is formed with worm teeth 27 meshing with a worm gear 27'. The latter is mounted on a 95 stud 28 driven by a pinion 29 which meshes in turn with the spring driven gear 23. The spindle has mounted thereon a gear 30 for driving a centrifugal governor of any suitable construction, indicated generally by 31. 100

The parts are so dimensioned that the housing 15 has an easy fit inside the opening 12 in the cabinet shelf. The base plate 13 extends out beyond the rib 14 to have a flange like portion 33 which is substantially greater in diameter than the opening in the shelf 11. Below the flange 33 is a seating gasket 34 which, for present purposes, may be considered as part of the base plate. 105 110

The spindle 26, above the base plate, is formed with a shoulder 34, on which seats the turntable 35.

In assembling the machine, the motor unit is first assembled and is dropped into the opening 12 with the flange or outer edge 33 of the base plate resting on the shelf as clearly appears in the drawing. The base plate may be secured in place by screws 36 or other suitable means. The turntable is then mounted on the spindle.

With such a construction, with the motor mechanism carried by bearings on the base plate, and with the base plate itself suspended from the top of the cabinet shelf, the spindle has the desired elevation. It will be seen, moreover, that through any number of machines, this elevation of the turntable will be uniform despite variations in the thickness of the cabinet itself.

The construction described not only attains the result just mentioned but it does so by a construction that is of further marked utility because of the ease and convenience of assembly. The motor mechanism is readily mounted in the bearings carried by the base plate and with one integral bearing and one separate one, the number of parts is reduced without sacrifice of speed in assembly. The motor mechanism once assembled with the base plate makes a compact unit. These units and the cabinets may be separately manufactured without regard to each other. Then, when brought together, it is only nec-

essary to drop the motor unit into the shelf opening and secure it in place, no complicated positioning or adjusting of parts being necessary. As a result, there is provided not only an effective machine but an extremely simple and economical one.

What is claimed is:

1. In a phonograph, and in combination, a base plate having a portion for seating on the top of a cabinet shelf to suspend the motor unit therefrom, a bearing bracket depending from said base plate, a motor housing, a turntable spindle and a governor shaft having bearings in said bracket, a driving connection between the motor and the spindle, a winding connection at the opposite side of the motor housing, and a bearing bracket depending from the base plate and supporting said winding connection, the motor housing being supported between the two brackets.

2. In a phonograph, in combination with a cabinet shelf having an opening therein, a motor base plate having a flange for suspending the plate from the top of the cabinet shelf, a depending flange inside said first named flange, a casing secured to said depending flange, bearings carried by the base plate, and a motor unit including a turntable spindle supported by said bearings.

In testimony whereof, I have hereunto set my hand.

CLINTON E. WOODS.
